Primary Examiner — Jennifer L Watkins(74) *Attorney, Agent, or Firm* — Hamre, Schumann, Mueller & Larson, P.C.(57) **CLAIM**

I claim the ornamental design for a mask liner, as shown and described.

DESCRIPTION

FIG. 1 is a top view of a mask liner;
FIG. 2 is a bottom view of the mask liner of FIG. 1;
FIG. 3 is a top perspective view of the mask liner of FIG. 1;
FIG. 4 is a bottom perspective view of the mask liner of FIG. 1;
FIG. 5 is a top view of the mask liner of FIG. 1 showing one of the tabs being folded;
FIG. 6 is a bottom view of the mask liner of FIG. 5;
FIG. 7 is a top perspective view of the mask liner of FIG. 5;
FIG. 8 is a further top perspective view of the mask liner of FIG. 5;
FIG. 9 is a bottom perspective view of the mask liner of FIG. 5; and,
FIG. 10 is a further bottom perspective view of the mask liner of FIG. 5.
The broken lines on the mask liner depict stitching and form no part of the claim.

1 Claim, 7 Drawing Sheets(56)
